CLAIM

The ornamental design for the fluid substance applicator, as shown and described.

DESCRIPTION

FIG. 1 is a perspective view of a fluid substance applicator; FIG. 2 is top view thereof; FIG. 3 is a bottom view thereof; FIG. 4 is a left side view thereof; FIG. 5 is a right side view thereof; FIG. 6 is a back view thereof; and, FIG. 7 is a front view thereof.

In the drawings, the broken lines show portions of a fluid substance applicator that form no part of the claim.
